ADJUSTABLE ORGAN BENCH

Hubert S. Shearin and Charles Riley, Cincinnati, Ohio,
assignors to Manual Arts Furniture Company, Cincinnati, Ohio

Filed Feb. 28, 1973, Ser. No. 336,434

Term of patent 14 years

Int. Cl. D6—01

U.S. Cl. D6—32

FIG. 1 is a perspective view of an adjustable organ bench having the new design.

FIG. 2 is a top plan view thereof.

FIG. 3 is a side elevational view thereof, the opposite side being the same.

FIG. 4 is an end elevational view thereof, the opposite ends being the same.

We claim:

The ornamental design for an adjustable organ bench, as shown and described.
